(57) **CLAIM**

The ornamental design for an outdoor HVAC unit as shown
and described.

DESCRIPTION

FIG. 1 is a front upper perspective view of an outdoor HVAC
unit, showing our new design;

FIG. 2 is a front view of the outdoor HVAC unit of FIG. 1;
FIG. 3 is a rear view of the outdoor HVAC unit of FIG. 1;
FIG. 4 is a right side view of the outdoor HVAC unit of FIG.
1;

FIG. 5 is a left side view of the outdoor HVAC unit of FIG.
1;

FIG. 6 is a top view of the outdoor HVAC unit of FIG. 1;
and,

FIG. 7 is a bottom view of the outdoor HVAC unit of FIG.
1.

The broken lines in the figures illustrate portions of the
design that form no part of the claimed design.
